Primary Examiner—Nelson C. Holtje

Assistant Examiner—Martha Thompson

[57] CLAIM

The ornamental design for a writing instrument, as shown and described.

DESCRIPTION

FIG. 1 is a front elevational view of a writing instrument showing our new design;

FIG. 2 is a rear elevational view;

FIG. 3 is a left side elevational view;

FIG. 4 is a top plan view; and,

FIG. 5 is a bottom, right front perspective view thereof.
